UNITED STATES PATENT OFFICE.

ELMER S. TANQUARY, OF LAWRENCEVILLE, ILLINOIS.

ATTACHMENT FOR STRINGED INSTRUMENTS.

Application filed April 14, 1922. Serial No. 552,486.

To all whom it may concern:

Be it known that I, ELMER S. TANQUARY, a citizen of the United States, residing at Lawrenceville, in the county of Lawrence 5 and State of Illinois, have invented certain new and useful Improvements in Attachments for Stringed Instruments; and I do hereby declare the following to be a full, clear, and exact description of the invention, such as will enable others skilled in the art to which it appertains to make and use the same.

This invention relates to stringed musical instruments of that type in which the performer causes the strings to vibrate by striking or picking them with the fingers or a picking device held in the fingers. It relates more particularly to an attachment to facilitate playing of Hawaiian music on a 20 guitar or similar instrument where the performer holds in the left hand a steel and in the right hand a picker that is moved across the strings while the steel held in the left hand is applied to the strings along the neck 25 of the instrument to produce various chords. In playing instruments of this character in the manner referred to the performer cannot properly fret the strings to produce true chords.

30 An object of the present invention is to enable true chords to be produced while playing stringed instruments in the manner described. In my Patent 1,302,451, patented April 29, 1919, I have described a means by which the strings may be fretted during the playing of an instrument with both hands in the customary manner of rendering Hawaiian music. In the device described in that patent a support independent 40 of the instrument was associated with a stop device so that by swaying the instrument during rendition of the music the stop device would be caused to press down different strings of the instrument whereby to produce different chords when those strings were swept by the fingers or picking device. In this improvement I have provided a stop device attached to the instrument and free of external support, the stop device being 50 disposed in position to be controlled and operated by the wrist or palm of the hand adjacent its junction with the wrist without interfering with the freedom of motion of the fingers of that hand used in picking the 55 strings.

In the accompanying drawings in which

like reference characters indicate like parts throughout the several views:

Figure 1 is a plan view of a guitar equipped with this improvement; 60

Figure 2 is a side elevation of the body thereof;

Figure 3 is a fragmentary cross section through the strings and sound board of a guitar on the line 3—3 of Figure 2, showing 65 the stop device in normal position;

Figure 4 is a similar section showing the improved stop depressed upon three of the strings;

Figures 5 and 6 are similar sections showing other working positions of the stop. 70

In order to exemplify the invention I have shown in the accompanying drawings one way in which it may be embodied in an ordinary guitar, in which 1 represents the 75 body, 2 the neck, 3 the tail piece and 4 the bridge, the strings 5 being attached to the tail piece 3 and stretched across the bridge to the tuning pegs. On the sound board of the guitar body, adjacent the bridge, are 80 two supplemental frets or fretting means 6 and 7. These frets 6 and 7 are spaced from the bridge the exact distance that the first two frets are ordinarily spaced from the nut of the guitar. The strings of course extend 85 over these frets without touching them. In the drawing I have indicated an ordinary so-called Hawaiian tuning. Fret 6 is arranged beneath the string marked C# and fret 7 is placed beneath the strings marked 90 A, C# and E. The edge of the fret 7 is depressed a little lower than the edge of the fret 6.

Overlying the strings A, C# and E is the stop device indicated as a whole by the 95 numeral 8. The stop device may be any movable means attached to the guitar in any suitable manner so as to remain normally out of contact with the strings but susceptible of being depressed by the forearm, wrist, or heel of the hand in such manner as to press different combinations of the strings A, C# and E into contact with the frets 6 or 7 whereby different chords may be produced by sweeping strings A, C# 100 and E. For purposes of illustration I have shown the stop device as comprising a body 9 having manipulating extensions or buttons 10 and 11 on its upper surface and stop elements 12 and 13 on its under surface, the 105 stop element 12 being of such a length as to engage only one string at a time, to wit,

the string C# while the stop element 13 is of such a length as to engage all three strings A, C# and E simultaneously when evenly depressed upon them. The described stop body 9 may be supported in any suitable manner from the guitar body so that it is normally held free of the strings but may be depressed bodily into contact with the three strings at once or may be so manipulated as to depress the strings C# and E or A and C#. The body 9 is shown connected to and supported by a spring or elastic wire 14 having a lateral clamping device 15 adapted to embrace the tail piece 15 and having an offset fulcrum point 16 adapted to engage the sound board of the guitar and hold the stop device normally free of the strings. The supporting string 14 elastically resists both bending and torsional forces. Obviously the mode of attachment would have to be different on guitars or other instruments without a tail piece. Stop elements 12 and 13 are so disposed with respect to the frets 6 and 7 that they may respectively press upon the strings rearward of the frets and depress them into contact with said frets.

With the attachment in place as shown in Figures 1 and 2, with the stop elements 12 and 13 out of contact with the strings, the first or tonic chord may be obtained by sweeping the strings which underlie the stop device. By pressing down on the manipulator or button 11, as indicated in Figure 5, the stop element 13 depresses the string A into engagement with the fret 7 and the stop element 12 presses the string marked C# into contact with the fret 6, whereby, by sweeping the strings, a second chord may be obtained. By pressing down the button or manipulator 10 so as to bring the opposite end of the stop element 13 into contact with the string marked E and the stop element 12 into contact with the string marked C#, strings A and C# will be depressed into contact with the frets 7 and 6, respectively, and a third chord may be obtained. By pressing the stop device uniformly and evenly down against the strings the stop element 13 will depress all three of the strings into contact with the fret 7, whereby a fourth chord—the accidental—may be obtained. Thus three extra chord changes may be had by the use of this improved fretting device and they may be produced without interfering with the fingers of the performer properly picking the strings and without the use of any external device as shown in my prior patent. The added frets may be of wood or any material found suitable for the purpose. I prefer to make the stop elements 12 and 13 of rubber or rubber composition and the block 9 of wood, although other materials may be used.

What I claim and desire to secure by Letters Patent is:

1. In a stringed instrument of the type in which the strings are adapted to be vibrated by the fingers of the performer, fretting means on the instrument, a stop device, a support attached to the instrument for holding said stop device normally out of contact with the strings but so mounted as to be bodily depressed and also rocked, to cause selected strings to engage the frets, by the arm or wrist of the performer without interfering with the freedom of movement of the fingers in playing the instrument.

2. A stringed instrument of the type in which the strings are adapted to be vibrated by the fingers of the performer, fretting means on the body of the instrument adjacent to the bridge, stop means elastically held above the strings adjacent the fretting means so as to be bodily depressed and also rocked and adapted to be depressed upon selected strings by the arm or wrist of the performer without interfering with the movement of the fingers in picking the strings.

3. In a stringed instrument of the type in which the strings are vibrated by the fingers of the performer, two frets suitably spaced from the bridge at the bridge end of the body, stop means elastically held above the frets and above the strings, and so mounted as to be bodily depressed and also rocked, and means whereby the stop means may be depressed upon selected strings by the arm of the performer without interfering with the freedom of movement of the fingers in picking the strings.

4. In a stringed instrument of the type in which the strings are adapted to be vibrated by the fingers of the performer, a fret on the body of the instrument adjacent the bridge and underlying one of the strings, a second fret spaced from the first named fret and underlying the two strings on each side of the first named string, a stop device elastically held above said strings, and means whereby said stop device may be manipulated by the arm or wrist of the performer so as to fret selected combinations of the strings to permit the sounding of different chords without interfering with the freedom of the fingers used in playing.

5. In a stringed instrument of the type in which the strings are adapted to be vibrated by the fingers of the performer, two frets suitably spaced at different distances from the bridge the fret nearest the bridge underlying one string and the other fret suitably spaced therefrom underlying said string and the two upon opposite sides thereof, the edge of the second fret being slightly lower than the edge of the first fret, a stop device having two stop elements, one

adapted to engage the string adjacent the first named fret and the other adapted to engage the strings adjacent the second named fret, and means for elastically retaining the stop device above the strings so as to permit it to be depressed into contact with the strings or rocked to either side by the arm or wrist of the performer whereby different chords may be produced without interfering with the freedom of movement of the fingers used in playing.

6. In an instrument having strings stretched over a bridge at one end and frets beneath said strings at the other end and in which the strings are adapted to be vibrated

by the fingers of a performer; the combination of additional fretting means adjacent the bridge, stop means and a yieldable support attached to the instrument adapted to hold said stop means normally out of contact with the strings, said stop means being disposed in position and adapted to press selected strings into contact with said additional fretting means, said stop means having manipulating means disposed in position beneath the wrist of a performer when his hand is in position to pick the strings.

In testimony whereof I affix my signature

ELMER S. TANQUARY.
